UNITED STATES PATENT OFFICE.

DAVIS BARNARD, OF LOS ANGELES, CALIFORNIA, ASSIGNOR TO BARNARD MANUFACTURING COMPANY, OF LOS ANGELES, CALIFORNIA, A CORPORATION OF CALIFORNIA.

CLOSURE MEANS FOR FUEL-HEATING DEVICES AND THE LIKE.

1,205,591.

Specification of Letters Patent.

Patented Nov. 21, 1916.

Application filed February 25, 1913. Serial No. 750,695.

To all whom it may concern:

Be it known that I, DAVIS BARNARD, a citizen of the United States, residing in the city of Los Angeles, State of California, have invented a new and useful Closure Means for Fuel-Heating Devices and the like, of which the following is a specification.

An object of this invention is to provide improved means to afford ready access to the interior of fuel heating devices and the like for cleaning the same.

The closure means provided by this invention consists of a spring-retained cap or cover, or plurality of such caps or covers, which may be readily removed by hand against the opposition of the spring or springs normally holding the same in place, said covers being as readily replaced by hand after the device provided with said covers has been cleaned.

The closure means of this invention are more particularly intended to be applied to the type of fuel heater illustrated in the accompanying drawings, but it is not intended to limit the invention to such use.

Referring to the accompanying drawings, which illustrate the invention, Figure 1 is a side elevation of the complete device, the 30 left hand portion of the view being sectioned. Fig. 2 is a cross section on line x^2-x^2 of Fig. 1. Fig. 3 is a side elevation showing the closures removed. Fig. 4 is a side elevation on a smaller scale to illustrate the flexible conduits to which the removable covers are connected.

Referring in detail to the drawings, which illustrate the preferred embodiment of the invention, 1 designates a four-way fitting having lateral branches 2 and 3 and vertically extending branches 4 and 5. The laterally extending branch 2 is normally closed by a closure cap 6, and the opposite lateral branch 3 is normally closed by a like closure cap 7. Said closure caps are yieldingly secured in the closed position by a pair of diametrically opposite spiral tension springs 8 and 9. Said tension springs are adapted to hold the closures in closed position as shown in Fig. 1, and are also adapted to hold said closures in the open position when said closures are removed and brought down to the position shown in Fig. 3.

In Fig. 4 the device is shown connected

up with the exhaust pipe of an engine. In 55 this view the cap 7 and the exhaust pipe 14 are connected by a flexible tube 15. A flexible tube 16 may also be attached to the other cap 6, said tube 16 leading to a vent pipe (not shown). The flexible tubes 15 and 16 60 enable the operator to remove the caps 6 and 7 without the use of tools to loosen couplings or disconnect other parts.

In the embodiment of the invention illustrated in the drawings, this device is shown 65 applied to a fuel heating device having a multiplicity of heating tubes 11, extending laterally therethrough, as seen in section in Fig. 2, and shown also to some extent in the sectioned portion of Fig. 1. It will be 70 understood, however, that this closing device may be applied to open ended tubular casings in general wherever it is desired to render the interior of the same easily accessible. The casing is provided on each end 75 with a lug 12 which seats in a notch 13 in the cap, to prevent rotation of the caps after they have been turned to bring the springs into the positions indicated in Figs. 1 and 2. The notches are so spaced that they engage the lugs when the covers have been rotated to the proper position.

When the caps are seated on the casing they are preferably turned so that the springs lie adjacent the branches 4-5 instead of 85 being disposed in the same horizontal plane, since in this position the caps are more difficult to remove and will not become accidentally displaced due to the weight of the tubes 15-16. When the caps are removed 90 they are rotated, due to the unequal pull of the springs, so that the springs lie in the same horizontal plane.

When the caps are to be removed they are first pulled outward slightly to disengage 95 the caps from the lugs and are then rotated to bring the springs into the same horizontal plane. With the springs in this position, the caps are then pulled outward and downward against the pull of the springs 100 and assume the position shown in Fig. 3. When the caps are in this position the tubes may be readily cleaned.

I claim:

1. A casing having oppositely arranged 105 open ends, a closure rotatably mounted on each end, springs extending longitudinally on opposite sides of the casing connected at

their ends to said closures and adapted to normally hold the closures to their seats, and a flanged abutment extending transversely from the casing adapted to be engaged by 5 the closures when they are removed from the ends of the casing.

2. A casing having oppositely arranged open ends, a closure adapted to seat on each of said ends, a plurality of tension springs 10 attached at their opposite ends to said closures and adapted to hold said closures to their seats, a transversely extending conduit projecting from said casing between said longitudinally extending springs, and a 15 flange on the end of said conduit, said clo-

sures being so shaped that they may engage between the casing and the flange, the points of attachment of the springs to the closures being such that the tension of the springs holds the closures in position against said 20 flange.

In testimony whereof I have hereunto signed my name in the presence of two subscribing witnesses at Los Angeles, in the county of Los Angeles and State of California, this 19th day of February 1913.

DAVIS BARNARD.
